Des. 229,079
Patented Nov. 6, 1973

229,079

CHILD'S RIDING VEHICLE

Robert E. Boyle, P.O. Box 7225,
St. Petersburg, Fla. 33734

Filed Mar. 17, 1972, Ser. No. 235,871

Term of patent 14 years

Int. Cl. D21—01

U.S. CL. D34—15 AJ

FIG. 1 is a front perspective view of a child's riding vehicle showing my new design;

FIG. 2 is a top plan view thereof;

FIG. 3 is a side elevational view thereof;

FIG. 4 is a front elevational view thereof;

FIG. 5 is a bottom plan view thereof; and

FIG. 6 is a rear elevational view thereof.

I claim:

The ornamental design for a child's riding vehicle, as shown.
